UNITED STATES PATENT OFFICE.

WILLIAM S. O'BRIEN, OF SAN FRANCISCO, CALIFORNIA.

DESIGN FOR A SPOON.

SPECIFICATION forming part of Design No. 22,561, dated June 27, 1893.

Application filed March 15, 1893. Serial No. 468,140. Term of patent 7 years.

To all whom it may concern:

Be it known that I, WILLIAM S. O'BRIEN, a citizen of the United States, residing at San Francisco, in the county of San Francisco and State of California, have invented a certain new and original Design for Spoons, of which the following is a specification.

The leading or characteristic features of my new and original design consist in so shaping the bowl of the spoon that when it is seen from the side, it suggests by its shape and exterior configuration and ornamentation, an ocean steamship of modern style; other features of originality are found in the surface ornamentation of the bowl.

In the drawings wherein is shown a spoon formed according to my design—Figure 1 is a side view thereof. Fig. 2 is a face view showing the interior or obverse of the bowl. Fig. 3 is a cross section on the line 3—3 of Fig. 2. Fig. 4 is a view showing the reverse of the spoon.

The bottom *a* of the bowl is more nearly flat than is customary in spoons of ordinary patterns, and the side walls *b* thereof rise from the bottom more nearly vertically, that is,

with less flare, than is usual. The outside surface of the side walls of the bowl are shaped and ornamented so that when seen from the side they have the appearance of that part of the hull of a modern ocean steamship which is above the water-line. This feature is shown in Fig. 1 of the drawings. The various ports, and holes,—such as for hawsers, for ventilation, and for light, &c.,—through the hull,—are indicated by stamping or engraving, and are represented at 2, 2, 2, in the drawings. Upon the inner face or obverse of the bowl there appears the representation of a fleet of modern warships resting in the water, as shown at 3 in Fig. 2. Upon the reverse of the bowl there are representations of war vessels of various types, as represented in Fig. 4.

What I claim is—

The design for a spoon substantially as set forth and shown.

In testimony whereof I affix my signature in presence of two witnesses.

WILLIAM S. O'BRIEN.
